UNITED STATES PATENT OFFICE.

AUGUST N. E. BOOS, OF NEW YORK, N. Y.

RECORDING APPARATUS.

Application filed March 13, 1924. Serial No. 698,845.

This invention relates to recording apparatus and has for its primary object to provide a very simply constructed apparatus for recording orders or sales in hotels, 5 restaurants or other commercial establishments.

It is another object of the invention to provide an apparatus of this kind in which both the individual sales records and the 10 checker's records are contained in locked compartments so that they cannot be changed.

With the above and other objects in view, the invention consists in the improved recording apparatus and in the form, construction and relative arrangement of its several parts as will be hereinafter more fully described, illustrated in the accompanying drawings, and subsequently incorporated in the subjoined claims.

In the drawings wherein I have illustrated one simple and practical embodiment of the invention and in which similar reference characters designate corresponding parts throughout the several views:

Figure 1 is a perspective view of my improved recording apparatus;

Fig. 2 is a sectional perspective view taken on the line 2—2 of Fig. 1.

In Figure 1 of the drawings I have illustrated my apparatus as designed for use by fifteen salesmen and one checker. As shown, a separate recording means is provided for each salesman. The checker's 30 compartment is provided with two recording devices, one of which is for the entry of duplicate records and the other for the entry of comments or remarks in connection with the different sales. The entire mechanism is housed within two separate casings herein designated as 99 and 100, each of which is hingedly mounted as at 101, 102, respectively, upon a suitable base plate 21. The front wall of each casing is provided 40 with a suitable lock, the lock for the casing of the salesmen's recording devices being indicated at 1 and that for the checking compartment being indicated at 2. The key to these locks is in the possession of the 45 proprietor, who alone can obtain access to the various records.

In use, the several salesmen must have the goods being sold by them properly checked and priced by the checker, the salesman then 55 entering the prices on his particular record, and the checker copying the several items

and prices on his record. The record of the individual salesman consists of a continuous paper strip drawn from a roller past the opening 4 in the top wall of the casing or 60 housing, the number or other symbol of the individual or salesman being indicated on the housing wall as shown at 3. The paper is fed past and beneath said opening by the salesman actuating the wheel 5 which projects upwardly through a slot in the casing wall. The upper portion of the opening 4 is covered by a glass 6 through which the entries inscribed on the paper sheet can be 65 read. However, after the entries have been 70 made and the wheel actuated in one direction to move the written entries beneath the glass plate 6, the wheel 5 may be locked against reverse movement by means not shown so that the entries can not be 75 changed. In each actuation of this wheel an alarm is sounded which calls the checker's attention to the fact that an entry has 80 been made. It is sometimes necessary to supply the salesmen with duplicate orders. This is done by the checker, who makes the proper entries in the spaces on his recorder as indicated at 8, 9, 10 and 11. The paper strip is drawn from the checker's compartment under the opening 24 in the top wall 85 of the casing or housing 99 and beneath the bar 13 at the lower edge of said opening. This bar provides a knife edge so that the individual entries may be torn off from the paper strip to be given to the salesmen. At 90 the same time a duplicate carbon record is made in the checker's compartment.

The checker's compartment also contains an additional recording means similar to that provided in each of the salesmen's compartments, the paper strip being drawn from one roll and re-wound upon another by actuating the wheel 17, the paper strip moving under the opening 15 and beneath the glass plate 16 covering a portion of said 95 opening. Upon this paper strip various comments or remarks may be entered relative to the various sales. The front wall of the casing for the salesmen's records is provided with spaced openings 18 and 19 and 100 the wall of the casing 99 with a similar opening 20, whereby when said casings are 105 unlocked, they may be readily lifted to an upright position upon their plate, as seen in Figure 2 of the drawings, so that access 110 may be had to the several compartments for the insertion of new paper rolls therein.

after the records have been removed at the end of the day's business. As illustrated in Figure 2 of the drawings, the bottom wall or plate 103 of each compartment is hinged 5 for movement with respect to the spaced partition or dividing walls and is held in closed position by suitable latch bolts 23.

As shown in Figure 2 of the drawings, paper rolls 25 and 26 are mounted in one 10 section of the checker's compartment, rotating loosely on shafts 85 and 96 respectively, said rolls providing original and duplicate copies, and a spool 27 for the carbon copy is also arranged in said compartment upon 15 which the carbon copy is wound. These several rolls are mounted in a suitable supporting frame 28, the several roller shafts being removably mounted in this frame.

In each waiter's or salesman's compartment, as shown in Figure 2, there is carried upon the hingedly mounted bottom wall thereof a paper roll 31, the paper strip being unwound from said roll and re-wound upon a suitable spool 32. This paper roll and 25 the spool are carried by shafts removably mounted in suitable frame supports 33.

To operate the device each waiter manipulates the wheel 5 of the paper roll 31 assigned to him whenever he has to make an 30 entry. Any suitable device such as a pawl and ratchet may be employed to prevent reverse rotation of each of the wheels 5 and any kind of an alarm may be employed to direct the checker's attention to the fact that 35 an entry has been made by one of the salesmen.

The checker's compartment is provided with a crank 50 to turn the shaft 96 and cause the paper roll 26 to be unwound. This 40 shaft 96 will be connected by gearing to the shaft of the other roll 25 so that the two rolls are unwound together. The strips of paper as they are unwound from the rolls 26 and 25 are caused to be moved with a 45 sheet of copying paper or carbon manifold paper between them; this copy paper being supported in any suitable manner. The paper from the roll 25 can pass to the outside of the casing 99 and be torn off along the 50 edge of the part 13, while the paper from the roll 26 after receiving a copy of whatever is written on the paper from the roll 25, is wound upon the roll or spool 27. This spool 2 may be actuated by suitable gearing (not 55 shown) and the shaft 96 may have a pawl or ratchet (also not shown) to prevent reverse rotation.

The opening 24 may have a plate 65 shown in Fig. 2 to provide a surface against which 60 the sheets of paper can be pressed when an

entry is made. The carbon manifold paper may be in the form of an endless loop, shown at 62 in Fig. 2, passing over the rollers indicated at 66. Both spools 26 and 27 will be enveloped by this loop so that as the spool 65 27 is wound up the spool 26 is unwound and the spool 27 will carry the duplicate records of all entries just above the spool 26. The loop 62 passes between a pair of rolls 66 along with the paper from both the rolls 70 25 and 26; the paper from the roll 25 being on top of the carbon manifold 62, and the paper from the roll 26 being under it.

From the foregoing description considered in connection with the accompanying drawings, the construction, advantages and manner of operation of the device will be readily understood. It will be seen that I have provided a recording apparatus which will be very useful in restaurants, hotels and other 75 large commercial establishments whereby accurate individual records may be kept and also a proper check maintained thereon, the permanent records being inaccessible so that they can be removed from the casing of the 80 apparatus only by the proprietor or one 85 having possession of the proper key.

While I have herein described an embodiment of the invention which I believe to be entirely practical, it will nevertheless be understood that the device is susceptible of more or less modification in the form, construction and relative arrangement of the several parts, and I accordingly reserve the privilege of adopting all such legitimate 90 changes in the form, construction and relative arrangement of the several parts as may be fairly embodied within the spirit and 95 scope of the invention as claimed.

I claim:

1. In a recording apparatus, a base, a casing hingedly connected thereto, a bottom wall hinged to the casing independently of the base and adapted to constitute a support for mechanism within the casing, and latch means to hold said bottom wall in closed position when the casing is swung away from the base.

2. In a recording apparatus, a base, a casing hingedly connected thereto, a bottom wall hinged to the casing independently of the base and adapted to constitute a support for mechanism within the casing, and means for locking the casing upon the base to prevent access to the interior of the casing.

In testimony that I claim the foregoing as my invention I have signed my name hereto.

AUGUST N. E. BOOS.
